UNITED STATES PATENT OFFICE.

HOWARD P. GARLAND, OF WEST BERKELEY, ASSIGNOR OF ONE-THIRD OF HIS RIGHT TO ANDREW J. GOVE, OF SAN FRANCISCO, CALIFORNIA.

WOODEN BOX.

SPECIFICATION forming part of Letters Patent No. 232,887, dated October 5, 1880.

Application filed January 31, 1880.

To all whom it may concern:

Be it known that I, HOWARD PRATT GARLAND, of West Berkeley, in the county of Alameda and State of California, have invented 5 a new and useful Improvement in the Manufacture of Wooden Boxes, of which the following is a specification.

This invention relates to the construction of wood packing-boxes the sides of which are 10 made from one continuous piece of board; and it consists in forming the joints of such boxes by means of a transverse channel or kerf having sloping sides, a plane bottom parallel with the fiber of the wood, and slight depressions 15 at the angle formed by the junction of the sides and bottom of the kerf, as more fully hereinafter set forth.

In the accompanying drawings, in which similar letters of reference indicate like parts, 20 Figure 1 is a plan of the strip of wood, showing grooves. Fig. 2 is a perspective view of box. Fig. 3 is a sectional view, showing the manner in which the lid and bottom are held in place. Fig. 4 is an enlarged view, in cross- 25 section, through one of the transverse channels, showing the horizontal plane between the depressed angles.

The strip of wood which is to form the sides A and ends B of my box is first planed, and 30 the channels A', where the joints are to be made, are formed by a channeling-tool having the corners slightly rounded, so that when the channel is struck out there will be left a slight depression, a a, at each corner of the base of the 35 channel, to correspond with the corners of the tool, and between these depressions, at the angles of the channel made by the cutting operation of the tool, remains a horizontal plane, b, parallel with the fiber of the wood, so that 40 in bending the fiber at the base of the channel will not become dissevered or broken by crowding together, as would be the case if an acute angle were formed at the base of the channel. Neither will there be an opening in the joints to

weaken the box, as in case a semicircular groove 45 were made in the base of the channel. A longitudinal channel, c c, is cut along the inner faces at the top and bottom of the strip, and the upper portions of these channels are beveled, as shown. The sides of the bottom and cover of the 50 box are chamfered to fit closely these channels, and the upper edge of one end of the box is cut away to admit of the cover being drawn off in the usual way. The two meeting ends of the strip are dovetailed, as shown at e. 55

In bending the strip to form the sides and ends the channels therein are first subjected to a jet of steam, which can be easily effected by tapping a steam-pipe in the works leading from a steam-boiler, after which the dovetailed 60 ends are dipped in a pan or vessel of hot glue, and then the strip is easily bent around the bottom of the box, which bottom has been previously laid upon a smooth and level place, and the dovetailed ends united. By this means 65 the joints will not be broken in bending, and the material composing the corners broken or crushed so as to be divided or separated by crowding the fiber, and stiff wooden boxes of great strength can be rapidly and cheaply 70 made without even a nail or dowel to hold the parts together.

Having thus described my invention, what I claim, and desire to secure by Letters Patent, is—

In the manufacture of wooden boxes, a blank having transverse channels or kerfs A', with sloping sides, a plane bottom, b, parallel with the fiber of the wood, and slight depressions a a, at each side thereof, substantially as and 80 for the purpose described.

In testimony that I claim the foregoing I have hereunto set my hand and seal this 27th day of December, 1879.

HOWARD P. GARLAND. [L. S.]
